(57) **CLAIM**

The ornamental design for an exercise bike, as shown and described.

DESCRIPTION

FIG. 1 is a front, right, and top perspective view of an exercise bike, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of the portion labeled FIG. 9 in FIG. 1.

FIG. 10 is an enlarged view of the portion labeled FIG. 10 in FIG. 1.

FIG. 11 is an enlarged view of the portion labeled FIG. 11 in FIG. 1.

FIG. 12 is an enlarged view of the portion labeled FIG. 13 in FIG. 1.

FIG. 13 is an enlarged view of the portion labeled FIG. 14 in FIG. 2; and,

FIG. 14 is an enlarged view of the portion labeled FIG. 12 in FIG. 8.

The evenly spaced broken lines shown in the drawings are included to show portions of the exercise bike that form no part of the claimed design.

The dot-dash broken lines shown in the drawings indicate an enlarged view of the exercise bike.

1 Claim, 14 Drawing Sheets
